MOLLIE M. SHAVER, OF LOS ANGELES, CALIFORNIA.

DOUCHE-TIP.

1,338,464.

Specification of Letters Patent. Patented Apr. 27, 1920.

Application filed September 9, 1918. Serial No. 253,171.

To all whom it may concern:

Be it known that I, MOLLIE M. SHAVER, a citizen of the United States, residing at Los Angeles, in the county of Los Angeles and State of California, have invented new and useful Improvements in Douche-Tips, of which the following is a specification.

This invention relates to a nozzle or tip for syringes and particularly pertains to 10 a nozzle which may be employed generally in making injections of liquid, such as enemas, and which is especially adapted for use in taking or administering vaginal douches.

15 Devices of the above character of the type now commonly on the market are formed of hard rubber, and syringe kits usually embody a series of nozzles of various sizes both as to length and diameter 20 and also of various shapes, some being substantially straight, while others are curved, the different varieties being provided to accommodate them to the various uses or conditions to which they are put. These 25 hard rubber nozzles are sometimes objectionable inasmuch as they are rigid and inflexible which not only occasions great discomfort in their use but also renders them liable to cause injury.

30 One of the primary objects of this invention is to provide a syringe nozzle or tip which is so formed and constructed that a single size and type of nozzle will serve the various uses for which numerous styles 35 of nozzles are now provided, and a further object is to provide a douche nozzle which is flexible and yieldable throughout so that it will bend under external pressure and readily follow the general curvatures of 40 the cavity walls with a minimum of danger of injury thereto and with the least possible discomfort, and which while flexible is of such rigidity as not to interfere with its insertion.

45 Another object is to provide the nozzle with discharge orifices so arranged as to insure a thorough flushing and cleansing action of the overlapping folds of the cavity walls, which renders the nozzle particularly 50 suitable for use in the treatment of vaginal disorders.

Other objects will appear hereinafter.

The invention is illustrated in the accompanying drawings in which;

55 Figure 1 is a view of the nozzle as seen in side elevation;

Fig. 2 is a view of the nozzle in longitudinal section illustrating the manner of constructing the nozzle tip and indicating the mode in which the jets of liquid are 60 projected from the nozzle;

Fig. 3 is an enlarged view of the nozzle tip as seen in end elevation.

Fig. 4 is a plan view of the nozzle;

Fig. 5 is an enlarged longitudinal section 65 of the nozzle tip.

In carrying out the invention the body portion of the nozzle, indicated at 4, is formed of flexible elastic tubing, the ordinary rubber tubing of commerce being 70 preferably employed, by which the nozzle is given the desired and essential characteristic of pliability whereby it may be caused to follow and substantially conform to the longitudinal curvatures of the cavities of 75 the body into which it is to be inserted.

An important feature of the invention resides in a tip 5 with which the outer end 80 of the tubular body is fitted, this tip serving to slightly stiffen the extreme end of the nozzle and provide a reinforcement by which the nozzle will be retained in shape and rendered durable. This tip comprises a cup-shaped member having tapering side walls 6 tapering from its closed end and 85 having its reduced end of an outside diameter greater than the inside diameter of the tube. The tip is inserted open end foremost into the end of the tube, the tube end being expanded to receive the tip, thus 90 forming the end portion of the nozzle with a slightly diverging outer wall which is rounded at its intersection with the end wall of the tip so as to form the nozzle with a convex end. The nozzle tip or end portion is thus slightly enlarged and formed with a blunt end, the enlargement serving to 95 slightly spread or separate the walls of the cavity and the blunt end serving as a guard against injury to the parts. 100

Discharge openings 7 are formed in the end of the tip 5 and preferably comprise a pair of elongated openings separated by a partition 8 of V-shaped cross section, the inclined walls of the partition acting to direct the jets discharged through the openings 7 in an outward direction in relation to each other, thus obviating the objection to a single central jet which is liable to cause injury in the case of vaginal treatments. 105

A series of perforations 9 are formed in

the wall of the tube adjacent its enlarged outer end through which lateral jets are projected in such manner as to effect a thorough cleansing action on the side walls 5 of the bodily cavity, which construction is particularly advantageous and important in using the nozzle in vaginal treatments on account of the overlapping or fold structure of the walls of the vagina.

10 The inner end of the nozzle is fitted with a hard rubber nipple 10 by which it may be coupled to the feed tube of a syringe in the usual manner.

In its operation the device is employed in 15 taking and administering enemas and douches in the ordinary mode, it being adapted for various uses by reason of its flexibility and the arrangement of the discharge openings in its walls and tip.

20 I am aware that rubber tubing has heretofore been employed in colon and rectal tubes which are only satisfactory for the one use for which they are intended, and accordingly I do not broadly claim as my

invention a nozzle embodying the sole 25 characteristic of flexibility, but my present invention more specifically resides in an improved yieldable tip combined with the flexible tubular body and also coupled with the arrangement of the discharge 30 openings and perforations by which the device is rendered suitable for various uses.

I claim:

A syringe nozzle comprising a curved 35 flexible and elastic tubular member of uniform diameter throughout having a series of perforations in its wall and adapted to bend to follow the general curvatures of the walls of the cavity into which it is inserted, and a yieldable cupshaped tip inserted in 40 the outer end of said tubular member and vulcanized thereto, said tip formed with elongated end discharge openings and which tip is of greater outside diameter than the inside diameter of the tubular 45 member, said tubular member being expanded at its end to receive the tip.

MOLLIE M. SHAFFER.
